US0D1025074S

(12) **United States Design Patent** (10) **Patent No.:** **US D1,025,074 S**
(45) **Date of Patent:** **** Apr. 30, 2024**

(54) **CASING COVER**

(71) Applicant: **CHENBRO MICOM CO., LTD.**, New Taipei (TW)

(72) Inventors: **Chiung-Wei Lin**, New Taipei (TW); **Yi-Chen Chen**, New Taipei (TW)

(73) Assignee: **CHENBRO MICOM CO., LTD.**, New Taipei (TW)

(**) Term: **15 Years**

(21) Appl. No.: **29/795,447**

(22) Filed: **Jun. 18, 2021**

(30) **Foreign Application Priority Data**

Apr. 9, 2021 (TW) 110301800

(51) **LOC (14) Cl.** **14-02**

(52) **U.S. Cl.**

USPC **D14/432**

(58) **Field of Classification Search**

USPC D14/367, 308, 356, 432, 439, 447, 440, D14/366, 313

CPC . G11B 33/0461; G11B 33/027; G11B 33/124; G11B 33/022; G11B 33/142

See application file for complete search history.

(57) **CLAIM**

The ornamental design for a casing cover, as shown and described.

DESCRIPTION

FIG. 1 is a front, bottom, right perspective view of a casing cover, showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Shading is used to illustrate the curvature of the part and not color.

1 Claim, 7 Drawing Sheets
